PULLEY CARRIER FOR GUY LINES

Application filed September 17, 1928. Serial No. 306,453.

This invention relates to devices for hanging the pulley block of a hoisting cable to a guy line, or the like, for use more especially in the raising and lowering of logs in car loading operations.

In apparatus of this character it is deemed necessary to have the hanger adjustably mounted upon the guy line so that the pulley block may be brought into a position suitable for loading operations; and, when thus regulated, provision must be made for securing the hanger to the guy-line.

Certain known pulley block supporting devices designed for this class of work are objectionable because of liability of being insecurely fastened to the supporting cable; others are objectionable because the fastening means therefor are difficult to manipulate in engaging and disengaging the same with respect to the supporting cable; and others, again, are objectionable because they subject a supporting cable to stresses and strains severly injurious to the cable.

The object of the present invention is to provide a hoisting-cable pulley-hanger which will overcome the objections above referred to and others; which will be convenient to shift from one position to another and be secured at a desired position to the supporting cable, and which will be peculiarly efficient in operation.

A further object is to provide a strong and durable construction of hanger frame, in which the securing parts are readily accessible.

These, and more specific objects, together with the advantages of the invention will appear in the following description.

The invention consists in the novel construction, adaptation and combination of parts hereinafter described and claimed.

In the accompanying drawing,—
Figure 1 is a view in longitudinal vertical section of pulley-block supporting devices embodying my invention, illustrated in engaged relation with a cable shown in side elevation; Fig. 2 is an end elevation and Fig. 3 is a view, partly in horizontal section of Fig. 1, with the cable omitted.

Fig. 4 is a pictorial side elevation to illustrate the application of the invention.

Referring first to Fig. 4, the numeral 5 designates a cable which, as shown, is utilized as a guy for a post 6, the lower end of the guy being secured to an anchor such, for example, as a tree stump 7. The purpose of the invention is to provide means for attaching to the cable 5 a means 8, hereinafter designated generally as the carrier, whereby the cable serves to support a pulley block 9 provided with a sheave 10 for a hoisting cable 11 employed in the loading of logs.

The carrier 8, preferably of cast metal, comprises two laterally spaced side plates 12 which are connected at the top by two longitudinally spaced block elements 13; and, intermediate their depths, each of the side plates 12 is provided at its inner side with a ledge 14 extending the entire length, preferably, of the carrier.

Between said block elements 13, the respective side plates 12 are provided with a pin 15 which is disposed transversely of the carrier and constitutes the axle for a peripherally grooved wheel 16.

In its underside each of the blocks 13 is provided with a longitudinal groove 17, which is arranged to slope upwardly from the inner to the outer end thereof, so that the grooves of both blocks taken together will be disposed in angular relation one with the other. The positioning of the block grooves, moreover, are such that the angle thereof is below the periphery of the groove of the wheel 16.

The side plates of the carrier below said wheel are apertured to receive a transversely disposed bolt 18 to support a link 19 which, in turn, engages with a hook or link 20 (Fig. 4) provided on the pulley block 9 to support the same.

The grooves 17 of the respective block elements 13 are provided with series of recesses 21 formed—as to shape and relative positions—to receive therein the successive twisted strands of opposing portions of the cable when pressed therewith by means of wedges 22, one for each carrier block 13. Each of said wedges is adapted to seat upon the car-

rier ledges 14 and has in its top a longitudinal channel 23 of a segmental circular shape in transverse section to accommodate the underside of the respective portion of the cable 5.

6 The wedge channels, unlike the grooves in the block elements 13, are smooth (not corrugated) to permit unobstructed endwise movement of the wedges with respect to the cable in effecting the upward flexing of the cable to have the strands thereof engage within the respective recesses 21 of the block element grooves.

7 The wedges are driven by hammer blows 15 into positions to set the cable into engaged relation, as above explained, with the carrier; and, to hold the wedges in positions to retain the cable in such engagement, I provide a screw threaded coupling bolt 24 extending through apertured lugs 25 of both wedges, the head 26 of the bolt engaging the lug of one wedge and a nut 27 screwed on the bolt engaging the lug of the other wedge.

8 To afford movement of the carrier to a selected position along the cable 5, the wedges 22 are withdrawn from the carrier.

9 The cable then straightens as represented by dotted lines 5¹ in Fig. 1 with a consequent disengagement of the cable from the carrier and transferring the weight thereof (together with that of other parts associated therewith) from the grooves 17 to the rotary wheel 16 which, tracking on the cable, renders easy the shifting of the carrier.

10 It is to be noted that the carrier is secured to the cable by bending the cable to cause the cable strands to engage in recesses provided therefor in the carrier structure.

11 The weight of the load is distributed substantially throughout the length of the carrier. It is also to be noted that the location of the load suspending bolt 18 at the mid-length of the carrier and intermediate the cable gripping portions of the carrier applies the load to the cable most effectively with a minimum of strains and stresses in the cable.

12 The construction and manner of using the invention will, it is thought, be understood 50 from the foregoing description of the illustrated embodiment of the invention.

13 What I claim is,—

14 1. In a pulley carrier adapted to be secured to a supporting cable, said carrier comprising longitudinally spaced block elements having upwardly and outwardly diverging grooves in the lower face and plate elements depending in parallel relation from the sides thereof, cable engaging means carried between said plates at both ends of the carrier, said means being arranged for movement longitudinally of the carrier and adapted to cooperate with said block elements for deflecting the cable upwardly into angularly engaged relation with the carrier.

15 2. In a pulley carrier for use with a supporting cable, said carrier comprising a pair of block elements spaced apart longitudinally of the carrier, plate elements rigid with and depending from the opposite sides of said block elements, a wheel rotatably mounted in the carrier between said block elements and adapted to bear upon a cable extending lengthwise through the carrier below said block elements, and wedge means adapted to cooperate with said block elements for deflecting the cable with respect to said wheel and into clamping relation with the carrier.

16 3. A pulley carrier adapted to be secured at a desired position upon a supporting cable, said carrier comprising two parallel plates depending from the sides of two block elements, a cable-bearing wheel mounted in the carrier between said block elements, a wedge carried between the plates at each end thereof and adapted to be adjusted into cable gripping relation with the respective block elements.

17 4. In a pulley carrier as defined in claim 3 wherein the wedges are provided with apertured lugs, and means extending through the lugs of both wedges for coupling the same together in their cable gripping positions.

18 5. A pulley carrier adapted to be secured to a cable, said carrier comprising two longitudinally spaced block elements having cable receiving grooves in their undersides arranged in angular upwardly diverging relation with each other, plates rigid with said block elements and depending from the sides thereof, wedges supported by said plates below the respective block elements and arranged for movement longitudinally of the carrier to cooperate with said block elements for gripping the carrier to the cable, and a wheel provided between said block elements and adapted to track upon the cable to support the carrier after the wedges have been withdrawn from their cable gripping positions.

19 6. A pulley carrier adapted to be secured to a supporting cable, said carrier comprising a pair of block elements connected together in spaced apart longitudinal disposition, a pair of wedges adjustably mounted in the carrier below the respective block elements and adapted when moved toward each other to force the cable into engaged relation with both of said block elements, and means for securing the wedges in their adjusted positions.

20 7. In apparatus of the character described, a pulley carrier adapted to be detachably secured to a supporting cable, said carrier comprising block elements and plate elements depending from opposite sides thereof, the under sides of said block elements being arranged to slope upwardly from the midlength

- of the carrier to the ends thereof, ledges provided upon the inner sides of said plates below the block elements, and a pair of complementary wedges mounted upon said ledges, said wedges being adapted to cooperate with said block elements to impart a bend to the cable and grip the latter between the respective wedges and block elements.
- 5 8. In apparatus as defined in claim 7, including means for coupling the wedges in their adjusted cable engaging positions.
- 10 9. In apparatus of the character described, a pulley carrier adapted to be secured to a cable, said carrier comprising side plate elements provided with ledge elements and rigidly connected together adjacent the top of the carrier by longitudinally spaced block elements, said block elements being provided in their undersides with longitudinally disposed grooves arranged to slope upwardly from the inner ends thereof to the respective extremities of the carrier, each of said grooves being formed to provide therein a series of recesses, wedges mounted upon said ledges for movement longitudinally of the carrier for elevating and bending the cable to cause the strands thereof to engage the carrier within the recesses of the respective grooves, and means connected to the side plates of the carrier for suspending a pulley from the carrier.
- 15 20 25 30 35 40 45 50 55 60 65
10. In apparatus of the character described, a pulley carrier adapted to be secured to a cable, said carrier comprising side plate elements provided with ledge elements and rigidly connected together adjacent the top of the carrier by longitudinally spaced block elements, said block elements being provided in their undersides with longitudinally disposed grooves arranged to slope upwardly from the inner ends thereof to the respective extremities of the carrier, wedges mounted upon said ledges for movement longitudinally of the carrier for elevating and bending the cable to engage the carrier within the respective grooves, and means connected to the side plates of the carrier for supporting a pulley on the carrier.

Signed at Sultan, Washington, this 31st day of August, 1928.

SEYMOUR W. HILLIER.
